US00D840357S

(12) **United States Design Patent** (10) **Patent No.:** **US D840,357 S**
(45) **Date of Patent:** **** Feb. 12, 2019**

(54) **CONTROL DEVICE**

(71) Applicant: **QINGDAO BRIGHT MEDICAL MANUFACTURING CO., LTD.**,
Qingdao, Shandong Province (CN)

(72) Inventor: **Dezheng Zhao**, Qingdao (CN)

(73) Assignee: **QINGDAO BRIGHT MEDICAL MANUFACTURING CO., LTD.**,
Qingdao (CN)

(**) Term: **15 Years**

(21) Appl. No.: **29/595,443**

(22) Filed: **Feb. 28, 2017**

(30) **Foreign Application Priority Data**

Aug. 30, 2016 (CN) 2016 3 0447195

(51) **LOC (11) Cl.** **13-03**

(52) **U.S. Cl.**

USPC **D13/168**; D24/186

(57) **CLAIM**

The ornamental design for control device, as shown and described.

DESCRIPTION

FIG. 1 is a perspective front view of a first embodiment of control device;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and

FIG. 8 is a front view thereof showing the control device.

FIG. 9 is a perspective front view of a second embodiment of control device;

FIG. 10 is a right side view thereof;

FIG. 11 is a left side view thereof;

FIG. 12 is a front view thereof;

FIG. 13 is a rear view thereof;

FIG. 14 is a top view thereof;

FIG. 15 is a bottom view thereof; and

FIG. 16 is a front view thereof showing the control device.

FIG. 17 is a perspective front view of a third embodiment of control device;

FIG. 18 is a right side view thereof;

FIG. 19 is a left side view thereof;

FIG. 20 is a front view thereof;

FIG. 21 is a rear view thereof;

FIG. 22 is a top view thereof;

FIG. 23 is a bottom view thereof; and,

FIG. 24 is a front view thereof showing the control device.

The broken lines are for illustrative purposes only and form no part of the claimed design.

1 Claim, 12 Drawing Sheets
